UNITED STATES PATENT OFFICE.

ULYSSES G. CAVE, OF LOUISVILLE, KENTUCKY.

AUTOGRAPHIC REGISTER.

1,102,210.

Specification of Letters Patent. Patented June 30, 1914.

Application filed April 24, 1913. Serial No. 763,360.

To all whom it may concern:

Be it known that I, ULYSSES GRANT CAVE, a citizen of the United States, resident of Louisville, in the county of Jefferson and

5 State of Kentucky, have made a certain new and useful Invention in Autographic Registers; and I declare the following to be a full, clear, and exact description of the same, such as will enable others skilled in the art 10 to which it appertains to make and use the invention, reference being had to the accompanying drawings, and to letters or figures of reference marked thereon, which form a part of this specification.

15 Figure 1 is a side view of the sales register. Fig. 2 is a plan view of the same. Fig. 3 is a section on the line 3—3, Fig. 1. Fig. 4 is a detail side view of the hollow casing with one side of the casing removed. Fig. 20 5 is a detail fragmentary section on the line 5—5, Fig. 4. Fig. 6 is a detail section on the line 6—6 Fig. 5. Fig. 7 is a detail perspective view of one of the platform plates.

The invention has relation to autographic 25 registers, having for its object to provide an improved device of this character for use in registering memorandums and sales in mercantile and other transactions, and the invention consists in the novel construction 30 and combinations of parts as hereinafter set forth.

In the accompanying drawings, illustrating 35 the invention, the numeral 1, designates a hollow frame or casing having a platform plate 2, and two rotary spindles 3 and 4, upon one of which is placed the paper supply or feed roll 5, and upon the other of which the paper upon which the record is made is wound to constitute the record roll 6.

40 The paper passes from the supply roll outwardly of the casing through transverse slot 7, at one end of the platform plate, traverses this plate longitudinally, and the outer sheet of paper is at its other or rear end held 45 down to the plate by means 8, consisting preferably of a transverse bar or strip struck upward from the end plate 8', of the casing. After the record is made the outer paper sheet is torn off at a straight edge, preferably constituted by a separate part 9. The 50 inner sheet of paper, upon which the record is made by an intermediate carbon sheet between the two paper sheets, passes into the casing again at the rear end thereof 55 through transverse slot 10, passing then reversely back under the platform plate to

the record spindle upon which it is wound, the record spindle being caused to turn with and in the opposite direction to that of the supply spindle, preferably by means of the 60 gearing connection 11.

The platform plate is removably connected with the casing, preferably by means of angular inward turned lateral flanges 12, having perforations 13, engaging transverse 65 rods 14, of the casing, said casing having one side 15 thereof, removable, the other side 16, carrying the transverse rods 14, and the side 15, having perforations 16', engaging the outer ends of said rods, so that after the side 70 15 is removed endwise from engagement with the rods, the platform plate which is held in place by the side 15, may be slid laterally from engagement with said rods.

The transverse slot 7, is located between 75 the forward end of the platform plate and the end or corner plate 8', of the casing, the lower paper sheet passing around a guide rod located adjacent to said slot, and consisting preferably of one of the rods 14; and 80 the outer paper sheet passing around a guide rod 18, separated from and located adjacent to the rod 14, the end plate 17, being located above or outside the plane of the platform plate, and the guide rods or anti-friction 85 rollers thereupon being located partly above or outside the plane of said plate, so that the two paper sheets may first pass around the guide rods and afterward both in superposed position pass, in a substantially 90 7, and over the platform plate.

The guide rods will keep the paper sheets separated from each other to avoid contact and adherence until these sheets pass from 95 the guide rods to the platform plate. And inasmuch as the guide rods or anti-friction rollers upon said rods have their outer surfaces located above the outer surface of the platform plate, frictional adhesion of the 100 paper sheets with the carbon sheet will also be avoided.

The carbon sheet is preferably coiled in a roll at one end and the roll placed in a laterally-open lateral recess 19, of the casing, one of the downturned or inturned sides of the platform plate serving to normally close the open side of this recess, so that when the platform plate is removed, the carbon roll may be placed in or removed 110 from its recess.

The carbon sheet passes from its roll trans-

versely over the platform plate between the inner and outer paper sheets and is at its other end preferably held down by means of a rod or strip 20, pivoted at one end to the frame 21, and acting to clamp the end of the carbon to the side of the casing at 22. When this pivoted strip is turned to one side, the free end of the carbon is disengaged from the clamp and the carbon roll, in position in the frame recess, may be unwound to provide another length of carbon paper to take the place of the old carbon.

In order to provide against undue strain upon or against breaking the paper sheets due to the different comparative sizes of the paper supply roll and the record roll as the supply roll diminishes in size and the record roll increases in size, means are provided consisting preferably of a spring 22, carried by the pinion 11, said spring having frictional engagement with the end 23, of the record spindle, to turn the record spindle when the pinion is turned by the gear 24, of the supply spindle, the frictional engagement serving to turn the record spindle as required at all times, but yielding under strain as the sizes of the two rolls vary.

It is preferred to use three superposed sheets of paper, wound upon the supply spindle, the two outer sheets passing over two of the guide rods 18, located usually beneath and guarded by the end plate 17, of the casing, and all three sheets of paper taking an angular bend around the guide rods and from the guide rods passing in a substantially straight manner through the transverse slot 7, and over the platform plate. This will avoid unnecessary bends in the paper and consequent frictional strain thereupon. When the three sheets of paper are employed, the carbon sheet will be carbonized upon both sides and will be located between the intermediate sheet and the lower or record sheet, the record impression being made in positive upon the lower sheet, and the impression upon the intermediate sheet being made in negative.

Means are provided to prevent lifting of the two outer paper sheets and the insertion of a card between the intermediate paper sheet and the lower sheet which would prevent the carbon impression being made upon the lower sheet and enable a false entry to be made without record or notice thereof, this means resisting any backward movement of the middle sheet, and consisting preferably of pointed spring prongs 25, having outward projection through transverse slot 26, below the bar 8, of the end plate 8', the outer paper sheets passing under the bar 8, in frictional contact with said prongs, which present in the direction of the movement of the paper, so that should the paper sheets be moved reversely for the purpose stated, the prongs will engage and tear the

paper, serving as a notice that the paper has been tampered with.

The hollow casing is preferably of rectangular prismatic form and provided with duplicate platform plates upon the four sides thereof, and with duplicate record and paper supply spindles and duplicate end plates at the four corners. The other duplicate parts needed are also provided.

The hollow rectangular prismatic casing is rotatably mounted upon a base 27, said base having at its forward end an extension 28, serving as a hand rest and support in making the notations upon the paper. Means are provided to hold each platform plate constituting a side of the casing as it comes uppermost in line with the extension 28, in the rotation of the casing upon the base, said means consisting preferably of a pin 29, seated in the side of the base at 30, and having engagement in turn with lateral recesses 31, of the casing. When the casing is to be rotated to bring another side and platform plate thereof uppermost, for entry of a sale of a different class, the pin is pulled outwardly against the tension of its spring 32, and the casing rotated until the next recess 31, comes in register with the pin, which will then have automatic engagement with the recess. Or when the casing is to be removed from the base, the pin is turned until a lateral extension 33, thereof, has stop engagement with the side of the base to hold the pin released. When the casing is replaced, the pin is turned to release it from the stop engagement, the spring carrying the pin again inward into engagement with said recess.

Means are provided to lock the casing to the base consisting preferably of a pivoted plate 34, engaging over the pivot projection 25, of the casing, and having a lock connection with the base at 36.

What I claim is:

1. An autographic register, comprising a hollow quadrangular casing having oppositely disposed upper and lower and forward and rear platform plates, a paper supply spindle and a record spindle located adjacent to each other at each of the four corners of said frame at each end of and between the platform plates, and a separate driving connection between each supply and record spindle.

2. An autographic register, comprising a hollow quadrangular casing having a side carrying transverse rods, oppositely disposed upper and lower and forward and rear platform plates having lateral flanges provided with perforations removably engaging said rods, a paper supply spindle and a record spindle located adjacent to each other at each of the four corners of said casing at each end of and between the platform plates and carried by said side of

the casing, a separate driving connection between each supply spindle and record spindle, the other side of said casing having bearing perforations engaging the other 5 ends of said rods and other ends of the supply and record spindles.

3. An autographic register, comprising a hollow quadrangular casing having a side carrying transverse rods, oppositely disposed upper and lower and forward and 10 rear platform plates having lateral flanges provided with perforations removably engaging said rods, a paper supply spindle and a record spindle located adjacent to 15 each other at each of the four corners of said casing at each end of and between the platform plates and carried by said side of the casing, a separate driving connection between each supply spindle and record spindle, the other side of said casing having 20 perforations engaging the other ends of said rods and the other ends of the supply and record spindles, a central pivotal shaft for said casing, a supporting frame for said 25 casing, and means upon said frame for holding said casing in position with a platform plate uppermost, one side of said casing having an inner open-end lateral recess for

a carbon roll and the other side of said casing having means to hold down the carbon sheet at this side.

4. An autographic register comprising a hollow quadrangular casing having a side carrying transverse rods and corner plates, oppositely disposed upper and lower and 30 forward and rear platform plates located between said corner plates and having lateral flanges provided with perforations removably engaging said rods, a paper supply 35 spindle and a record spindle located adjacent to each other at each of the four corners of said casing at each end of and between the platform plates and carried by said side of the casing, a separate driving connection between each supply spindle and record 40 spindle, the other side of said casing having bearing perforations engaging the other 45 ends of said rods and the other ends of the supply and record spindles.

In testimony whereof I affix my signature, 50
in presence of two witnesses.
